PUSH BUTTON DOOR HANDLE

Gerald V. Jakeway, Grand Rapids, Mich., assignor to Keeler Brass Company, Grand Rapids, Mich.

Application July 23, 1956, Serial No. 599,568

5 Claims. (Cl. 292—336.3)

This invention relates to push button door handles adapted for use on doors of automobiles, refrigerators and the like.

The main objects of this invention are:

First, to provide a push button door handle adapted for use on automobiles, refrigerators and the like which may be assembled as a unit and installed as such and one in which the parts are associated to withstand severe usage and are not likely to get out of repair.

Second, to provide a push button door handle having these advantages in which the parts may be quickly and easily assembled and disassembled and one in which a noncircular push button is effectively supported to receive the thrust applied to any portion thereof without cocking or substantial binding.

Objects relating to details and economies of the invention will appear from the description to follow. The invention is defined and pointed out in the claims. A preferred embodiment of the invention is illustrated in the accompanying drawing, in which:

Fig. 1 is a fragmentary front elevational view of a handle embodying my invention applied to a door which is conventionally indicated.

Fig. 2 is an enlarged fragmentary view mainly in section on a line corresponding to line 2—2 of Fig. 1.

Fig. 3 is a fragmentary underside view of the handle.

Fig. 4 is a fragmentary view in section on a line corresponding to line 4—4 of Fig. 3.

Fig. 5 is a fragmentary view on a line corresponding to line 5—5 of Fig. 2.

Fig. 6 is a perspective view of the push button and stem in disassembled relation.

Fig. 7 is a fragmentary view illustrating details of the means for attaching a handle to a door.

In the accompanying drawing 1 represents a portion of a door such as an automobile door and 2 represents a latch provided with a latch actuating member or element 3. These parts are conventionally illustrated and it will be understood that they are varied in use and that portions of the handle are shaped to fit a door of a particular shape.

The handle comprises a grip portion 4 which merges into a head portion 5. The head portion has an undercut portion 6 provided with a socket 7 open at both ends and having an inwardly projecting flange 8 at its outer end providing an inwardly facing stop shoulder 9.

The cupped push button 11 is of flattened cross section shaped to correspond to the shape of the socket and dimensioned to be slidable therein. The push button is desirably formed as a sheet metal stamping and has an outwardly projecting stop flange 12 at its inner end. This coacts with the shoulder 9 to limit the outward movement of the push button which is introduced in the socket from its inner end. Desirably a gasket 13 is arranged on the flange 12 to seal the joint between the push button and the flange 8 when the push button is in its projected or normal position.

The push button stem 14 is provided with a head 15

2

seated within the push button and shaped to nonrotatably seat in the noncircular push button. The elongated head of the stem extends the full length of the push button so that tilting of the push button on the head does not occur in the event of pressure on one end of the push button instead of centrally thereof.

The stem is adapted to coact with the actuating element 3 of the latch as illustrated in Fig. 2. The stem is reciprocatingly supported in the tubular guide 16 fixedly mounted on the support or abutment member 17 which in the embodiment illustrated has an upwardly offset central portion 18 with an opening therein receiving the inner end of the tubular guide which is upset at 19 and 20 on the inner and outer sides of the support member. The support member is desirably a sheet metal stamping.

The coil spring 21 embraces the guide tube seated on the support member with its outer end in thrust engagement with the head of the stem. The head of the stem is preferably shouldered at 22 to receive the outer coil of the spring which prevents lateral sliding movement thereof. The seating of the spring on the support member in surrounding relation to the guide tube with its outer end in engagement with the shoulder 22 of the stem prevents the spring from coming into contact with the stem and eliminates noise in operation of the push button.

The support member 17 is detachably secured by screws 25 threaded into bores provided therefore in the socket wall, one bore being shown in Fig. 2.

With this arrangement of parts the handle may be mounted on the door as an assembled unit. The handle is provided with an internally threaded bore 26 adapted to receive an attaching screw 27, see Fig. 7. The attaching means for the outer end of the handle is not illustrated but it may be tapped to receive a screw disposed through the wall of the door from the inner side thereof. The wall has an opening 28 adapted to receive the inner end of the socket as illustrated in Fig. 4. The wall is preferably provided with a reinforcing plate 29 secured upon the inner side thereof.

The push button is desirably formed as a stamping. The push button stem 14 may be formed of a section of rod and its head 15 integral therewith. The stem guide is mounted on the support or abutment member which is detachably secured by the screws 25. The parts can be assembled with the socket by positioning the push button in the socket, the stem with its head in proper relation to the push button, positioning the coil spring on the stem, slipping the stem guide over the stem, and attaching the support 17 to the socket by inserting the screw 25.

The cutback of the socket member results in a protective overhang for the push button as is illustrated and positions the push button to be easily engaged by the thumb of a hand grasping the grip of the handle.

The parts, as stated, may be easily assembled and are freely disassembled simply by removal of the screws 25, and as stated the handle may be mounted as a unit after being assembled.

I have illustrated and described my invention in a highly practical embodiment thereof. I have not attempted to illustrate or describe other adaptations as it is believed this disclosure will enable those skilled in the art to embody or adapt my invention as may be desired.

Having thus described the invention, what is claimed as new and is desired to secure by Letters Patent is:

1. A handle comprising a grip and a head portion into which the grip merges, the head portion having an undercut portion provided with a socket open at both ends and having an inwardly facing shoulder at its outer end, said socket being of flattened horizontal section and having an opening in one side thereof, a cupped push button cross-sectionally flattened to conform to said socket and

provided with an outwardly projecting flange at its inner end coacting with said shoulder of said socket to limit the outward movement of the push button, said push button being insertable and removable from the inner end of the socket, a support member detachably mounted on the inner end of said socket, a tubular stem guide fixedly secured to said support member to project inwardly therefrom, a push button stem reciprocatingly supported in said guide and provided with an elongated head supportedly engaged with and removably and nonrotatably seated within said push button, and a coil spring seated on said support member in embracing relation to said stem guide with its outer end in thrust engagement with said stem head, said stem, push button and spring being retained in assembled relation within said socket and to each other by said removable support member.

2. A handle comprising a grip and a head portion into which the grip merges, the head portion having a socket open at both ends and having an inwardly facing shoulder at its outer end, a cupped push button provided with an outwardly projecting flange at its inner end coacting with said shoulder of said socket to limit the outward movement of the push button, said push button being insertable and removable from the inner end of the socket, a support member detachably mounted on the inner end of said socket, a tubular stem guide fixedly secured to said support member to project inwardly therefrom, a push button stem reciprocatingly supported in said guide and provided with a head supportedly engaged with and removably and nonrotatably seated within said push button, and a coil spring seated on said support member in embracing relation to said stem guide with its outer end in thrust engagement with said stem head, said stem, push button and spring being retained in assembled relation within said socket and to each other by said removable support member.

3. A handle comprising a grip and a head portion into which the grip merges, the head portion having an undercut portion provided with a socket open at both ends and having an inwardly facing shoulder at its outer end, said socket being of flattened section, a cupped push button cross-sectionally flattened to conform to said socket and provided with an outwardly projecting flange at its inner end coacting with said shoulder of said socket to limit the outward movement of the push button, said push button being insertable and removable from the inner end of the socket, a support member detachably mounted on the inner end of said socket, a tubular stem guide mounted on said support member to project inwardly therefrom, a push button stem reciprocatingly supported in said guide and provided with an elongated head removably and nonrotatably seated within said push button, and a coil spring seated on said support member in embracing relation to said stem guide with its outer end in thrust engagement with said stem head, said stem, push button

and spring being retained in assembled relation within said socket and to each other by said support member.

4. A handle comprising a grip and a head portion into which the grip merges, the head portion having an undercut portion provided with a socket open at both ends and having an inwardly facing shoulder at its outer end, a cupped push button provided with an outwardly projecting flange at its inner end coacting with said shoulder of said socket to limit the outward movement of the push button, said push button being insertable and removable from the inner end of the socket, a support member detachably secured to the inner end of said sockets, a tubular stem guide mounted on said support member to project inwardly therefrom, a push button stem reciprocatingly supported in said guide and provided with a head removably seated within said push button, and a coil spring seated on said support member in embracing relation to said stem guide with its outer end in thrust engagement with said stem head, said stem, push button and spring being retained in assembled relation within said socket and to each other by said support member.

5. A handle comprising a grip and a head portion into which the grip merges, the head portion having an undercut portion provided with a socket open at both ends and having an inwardly facing shoulder at its outer end, said socket having an opening in one side thereof, a cupped push button, said socket and push button having coacting stops limiting the outward movement of the push button within the socket, a support member removably secured to said head portion, a tubular stem guide fixedly secured to said support member, a push button stem reciprocatingly supported in said guide provided with a head removably seated within said push button, and a coil spring seated on said support member in embracing relation to said stem guide with its outer end in thrust engagement with said stem head, said stem, push button and spring being retained in assembled relation within said socket and to each other by said support member.
